OIL REFINING SYSTEM

William T. Hancock, Long Beach, Calif.

Application March 4, 1938, Serial No. 193,935

9 Claims. (Cl. 196—107)

This invention relates generally to the refining of petroleum oils, and has to do particularly with an improvement in systems wherein an oil, preferably a suitable cracking stock, initially is preheated below the cracking temperature, and then is subjected to cracking followed by fractionation.

In the present type of refining system the charging stock is first preheated and then forced by pump through a cracking still, the cracked oil ultimately being treated or fractionated in any suitable manner. Ordinarily the pump forcing the preheated oil through the cracking still operates at an inlet pressure corresponding to the preheater outlet pressure, which pressure may be subject to considerable variation, because of changing operating conditions, with relation to the cracking still outlet pressure. Consequently the load on the pump discharging to the cracking still is subject to variation in accordance with the changing differential between the pump inlet and outlet pressures. It is desirable, for obvious reasons, that the pressure and throughput rate under which the cracking still is operated be stable and uninfluenced by variations in the relative outlet pressures and throughput of the preheating and cracking stills, and accordingly it is the principal object of this invention to insure that desirable stability in this type of refining system.

In accordance with the invention, I provide what may be termed a pressure balance column, having one section or chamber through which the preheated charging stock flows to the cracking still feed pump, and another chamber through which the cracked oil stream is discharged by the pump from the cracking still to the fractionating equipment. Under typical operating conditions the oil is cracked under substantial pressure, for example in the neighborhood of 150 lbs. per sq. in. Although the preheated oil and cracked oil flow through the pressure balance column in separate streams, the chambers within the column are in communication so that the preheated oil is taken by the pump under pressure corresponding substantially to the cracking still outlet pressure. By thus avoiding possible substantial variations in the pressure differential under which the pump is required to operate, it is made possible to greatly stabilize the operation of the system as a whole. To this same end, the pressure balance may be adapted to serve a further purpose in providing a surge chamber to compensate for temporary excess in the rate of oil discharged from the preheating still over

the rate at which the oil has been put through the cracking still. As will appear, the pressure balance column may serve still further purposes, such as to effect a substantial degree of heat exchange between the cracked oil and preheated oil streams, to release preheated oil vapors into the cracked vapor stream, and to accomplish an intermediate fractionation of the cracked oil ahead of the final fractionating stages.

The various objects and operation of the invention will perhaps most readily be understood and explained to best advantage by reference to the accompanying drawing in flow sheet form, showing a typical refining system embodying the invention in one of its illustrative and preferred forms. It will be understood however that various changes and modifications may be made, particularly in the structural form and details of the pressure balance column, without departure from the intended spirit and scope of the invention.

A suitable charging stock, for example gas oil, is supplied through line 10 to the pump 11 which forces the oil through the preheating coil 12. For purposes of illustration, coil 12 is shown in a preheating still 13 separate from the cracking still 14, although it will be understood that if desired, the preheating and cracking coils may be incorporated in a single still structure. The oil is preheated in the still 13 to a suitable temperature, for example around 600° F., and is discharged through line 15 to an apparatus generally indicated at 16, to which I have referred as the pressure balance column. The latter, in the typical form shown, comprises a shell 17 containing upper and lower communicating chambers 18 and 19 separated by wall 20. Upper chamber 18 preferably serves as a dephlegmating or fractionating zone, being vertically elongated and provided with perforated plates 21 or other suitable means for securing intimate contact between the rising cracked vapors and down flowing reflux, as will later appear. Chamber 19 constitutes a lower zone through which the preheated oil flows from line 15 to the outlet 22, thence to be forced under pressure by pump 23 through line 24 of the cracking coil 25.

The cracked oil stream, heated to a temperature between 900° F. to 1100° F. for example, preferably is discharged through line 26 into a suitable reaction chamber 27 preliminary to the delivery of the cracked vapors through line 28 into chamber 18. Carbon and unvaporized residuum separated from the cracked oil stream in reaction chamber 27, are removed from the

system by way of line 29, so that only uncontaminated and vaporized hydrocarbons pass from the reaction chamber into the dephlegmating chamber 18. The cracked vapors are subjected to reflux condensation in flowing upwardly through the perforated plates in chamber 18. The reflux condensate is withdrawn from the base of the chamber through outlet 30, and the vapors are withdrawn through line 31 to be subjected to further fractionation. A portion or all of the reflux condensate removed from chamber 18 may be recirculated for further cracking in coil 25, by way of the valve controlled line 32 connecting with the preheated oil line 22.

15 The cracked oil vapors leaving column 16 may be subjected to final fractionation in any suitable manner, for example by introducing the vapors at 33 to the base of fractionating column 34 wherein fractions heavier than gasoline are condensed and removed through line 35. A portion of the condensate may be taken through line 36 and supplied by way of line 37 to the upper part of chamber 18 to reflux the cracked oil vapors introduced thereto. The system may be operated to produce in the fractionating column 34 reflux condensate suitable for recirculation to the cracking still, in which event, all or a portion of the condensate may be discharged through lines 36 and 38 to be combined with the preheated oil flowing through line 24 to the cracking still. Vapors leaving the fractionating column are passed through line 40 to final condenser 41 and thence to receiver 42 from which the distillate is removed through line 43 and fixed gases through line 44. A substantial pressure, for example of about 150 lbs. per sq. in., or above, is maintained on the oil undergoing cracking, by a suitable pressure regulating valve placed beyond the pressure balance column, for example at 45 between the pressure balance column and the fractionating column, or at 46 beyond the fractionating column.

45 A pressure balance between the preheated oil stream flowing from coil 12 to the cracking coil 25, and the cracked oil stream at the high pressure side of the pressure regulating valve, is maintained by providing pressure communication between chambers 18 and 19. Typically, the pressure connection between the chambers 50 may comprise a pipe 47 extending upwardly from the chamber partition 20 within chamber 18 to a point above the uppermost of the perforated plates 21. In addition to maintaining the pressure balance between chambers 18 and 19, pipe 55 47 also provides a passage through which any light vapors within chamber 19 are released into the cracked oil vapors, to be removed with the latter for fractionation in column 34. It will be observed that by placing chambers 18 and 60 19 in pressure balance, the pressures at opposite sides of the pump 23 are in balance except for the differential corresponding substantially to the pressure drop through the cracking still 14. As a result, the load on the pump is reduced to the point of low power requirement, and the constancy and efficiency of the pump operation are such as to effectively stabilize the operation of the entire system.

70 Thus column 16 serves the several functions of maintaining substantially a pressure balance between the preheated and cracked oil streams beyond their respective heating coils, and a low pressure differential between the suction and discharge sides of pump 23; also of fractionating 75 the cracking oil vapors, and by-passing to the

cracked vapor stream light oil fractions vaporized in the preheating stage. Other features incident to the operation of the column, are the maintenance of some heat transfer between the preheated oil stream and the cracked reflux condensate, and also the capacity of chamber 19 to serve as a surge chamber and thereby to compensate for any variations in the rates of oil discharge to the preheating and cracking coils by pumps 11 and 23.

10 I claim:

1. In a petroleum refining system in which oil is passed under substantial pressure through a preheater and then through a cracking still, a column comprising a vertically extending shell, a wall dividing the interior of said shell into upper and lower chambers and preventing liquid from flowing from the upper chamber into the lower chamber, means for passing preheated oil from said preheater through one of said chambers, a pump for then discharging the preheated oil to said cracking still, means for passing cracked oil vapors from the cracking still through the other of said chambers separately from the preheated oil flowing through the column, and means providing a pressure balance connection between the chambers to maintain the preheated and cracked oil leaving said preheater and cracking still under substantially the same pressure, whereby the pressure at the inlet side of said pump is made to correspond substantially to the pressure of the oil leaving the cracking still.

15 2. In a petroleum refining system in which oil is passed under substantial pressure through a preheater and then through a cracking still, a column comprising a vertically extending shell, a wall dividing the interior of said shell into upper and lower chambers and preventing liquid from flowing from the upper chamber into the lower chamber, means for passing preheated oil from said preheater through one of said chambers, a pump for then discharging the preheated oil to said cracking still, means for passing cracked oil vapors from the cracking still through the other of said chambers separately from the preheated oil flowing through the column, means subjecting the cracked oil vapors to reflux condensation within the last mentioned chamber, and means providing a pressure balance connection between the chambers to maintain the preheated and cracked oil leaving said preheater and cracking still under substantially the same pressure, whereby the pressure at the inlet side of said pump is made to correspond substantially to the pressure of the oil leaving the cracking still.

20 3. In a petroleum refining system in which oil is passed under substantial pressure through a preheater and then through a cracking still, a column comprising a vertically extending shell, a wall dividing the interior of said shell into upper and lower chambers and preventing liquid from flowing from the upper chamber into the lower chamber, means for passing preheated oil from said preheater through one of said chambers, a pump for then discharging the preheated oil to said cracking still, means for passing cracked oil vapors from the cracking still through a reaction chamber wherein unvaporized residue is removed, and then through the other of said chambers separately from the preheated oil flowing through the column, and means providing a pressure balance connection between the chambers to maintain the preheated and cracked oil leaving said preheater and cracking still un-

der substantially the same pressure, whereby the pressure at the inlet side of said pump is made to correspond substantially to the pressure of the oil leaving the cracking still.

5 4. In a petroleum refining system in which oil is passed under substantial pressure through a preheater and then through a cracking still, a column comprising a vertically extending shell, a wall dividing the interior of said shell into upper and lower chambers and preventing liquid from flowing from the upper chamber into the lower chamber, means for passing preheated oil from said preheater through one of said chambers, a pump for then discharging the preheated oil to said cracking still, means for passing cracked oil vapors from the cracking still through a reaction chamber wherein unvaporized residue is removed, and then through the other of said chambers separately from the preheated oil flowing through the column, means subjecting the cracked oil vapors to reflux condensation within the last mentioned chamber, and means providing a pressure balance connection between the chambers to maintain the preheated and cracked oil leaving said preheater and cracking still under substantially the same pressure, whereby the pressure at the inlet side of said pump is made to correspond substantially to the pressure of the oil leaving the cracking still.

30 5. In a petroleum refining system in which oil is passed under substantial pressure through a preheater and then through a cracking still, a column comprising a vertically extending shell, a wall dividing the interior of said shell into upper and lower chambers and preventing liquid from flowing from the upper chamber into the lower chamber, means for passing preheated oil from said preheater through the lower chamber, a pump for then discharging the preheated oil to said cracking still, means for passing cracked oil vapors from the cracking still through the upper chamber separately from the preheated oil flowing through the column, and means providing a pressure balance connection between the chambers to maintain the preheated and cracked oil leaving said preheater and cracking still under substantially the same pressure, whereby the pressure at the inlet side of said pump is made to correspond substantially to the pressure of the oil leaving the cracking still.

50 6. In a petroleum refining system in which oil is passed under substantial pressure through a preheater and then through a cracking still, a column comprising a vertically extending shell, a wall dividing the interior of said shell into upper and lower chambers and preventing liquid from flowing from the upper chamber into the lower chamber, means for passing preheated oil from said preheater through the lower chamber, a pump for then discharging the preheated oil to said cracking still, means for passing cracked oil vapors from the cracking still through a reaction chamber wherein unvaporized residue is removed, and then through the upper chamber separately from the preheated oil flowing through the column, means subjecting the cracked oil vapors to reflux condensation within the last mentioned chamber, and means providing a pressure balance connection between the chambers to maintain the preheated and cracked oil leaving said preheater and cracking still under substantially the same pressure, whereby the pressure at the inlet side of said pump is made to correspond substantially to the pressure of the oil leaving the cracking still.

7. In a petroleum refining system in which oil is passed under substantial pressure through a preheater and then through a cracking still, a column comprising a vertically extending shell, a wall dividing the interior of said shell into a lower chamber and an upper chamber and preventing liquid from flowing from the upper chamber into the lower chamber, means for passing preheated oil from said preheater through said lower chamber, a pump for then discharging the preheated oil to said cracking still, said lower chamber having sufficient volume to permit the preheated oil to surge therein, means for passing cracked oil vapors from the cracking still through said upper chamber separately from the oil flowing through said lower chamber, means for subjecting the cracked oil vapors to reflux condensation within the upper chamber, means for fractionating the cracked oil vapors uncondensed in said upper chamber, and means providing a pressure balance connection between the chambers to release vapors from the lower chamber into the upper chamber and to maintain the preheated and cracked oil leaving said preheater and cracking still under substantially the same pressure, whereby the pressure at the inlet side of said pump is made to correspond substantially to the pressure of the oil leaving the cracking still.

8. In a petroleum refining system in which oil is passed under substantial pressure through a preheater and then through a cracking still, a column comprising a vertically extending shell, a wall dividing the interior of said shell into a lower chamber and an upper chamber and preventing liquid from flowing from the upper chamber into the lower chamber, means for passing preheated oil from said preheater through said lower chamber, a pump for then discharging the preheated oil to said cracking still, said lower chamber having sufficient volume to permit the preheated oil to surge therein, means for passing cracked oil vapors from the cracking still through said upper chamber separately from the oil flowing through said lower chamber, means for subjecting the cracked oil vapors to reflux condensation within the upper chamber, means for passing reflux condensate from said upper chamber to the cracking zone, means for fractionating the cracked oil vapors uncondensed in said upper chamber, and means providing a pressure balance connection between the chambers to release vapors from the lower chamber into the upper chamber and to maintain the preheated and cracked oil leaving said preheater and cracking still under substantially the same pressure, whereby the pressure at the inlet side of said pump is made to correspond substantially to the pressure of the oil leaving the cracking still.

9. In a petroleum refining system in which oil is passed under substantial pressure through a preheater and then through a cracking still, a column comprising a vertically extending shell, a wall dividing the interior of said shell into a lower chamber and an upper chamber and preventing liquid from flowing from the upper chamber into the lower chamber, means for passing preheated oil from said preheater through said lower chamber, a pump for then discharging the preheated oil to said cracking still, said lower chamber having sufficient volume to permit the preheated oil to surge therein, means for passing cracked oil vapors from the cracking still through said upper chamber sep-

arately from the oil flowing through said lower chamber, means for subjecting the cracked oil vapors to reflux condensation within the upper chamber, means for combining reflux condensate from said upper chamber with the preheated oil flowing to the cracking still, means for fractionating the cracked oil vapors uncondensed in said upper chamber, and means providing a pressure balance connection between the cham-

bers to release vapors from the lower chamber into the upper chamber and to maintain the preheated and cracked oil leaving said preheater and cracking still under substantially the same pressure, whereby the pressure at the inlet side of said pump is made to correspond substantially to the pressure of the oil leaving the cracking still. 5

WILLIAM T. HANCOCK.
